UNITED STATES PATENT OFFICE.

LOUIS STEINBERGER, OF NEW YORK, N. Y.

INSULATOR FOR HIGH VOLTAGES.

No. 839,665.

Specification of Letters Patent.

Patented Dec. 25, 1906.

Application filed June 28, 1905. Serial No. 266,407.

To all whom it may concern:

Be it known that I, LOUIS STEINBERGER, a citizen of the United States, and a resident of the city of New York, borough of Brooklyn, in the county of Kings and State of New York, have invented a new and Improved Insulator for High Voltages, of which the following is a full, clear, and exact description.

My invention relates to insulators for electric conductors, and especially to insulators for conductors conveying currents of high potential.

The main object of my insulator is to prevent any leakage of current or the possibility of the formation of a destructive arc between the conductor and the line-support, such as a partition or wall, and also to prevent the leakage of the current and the formation of arcs between the conductors and adjacent bodies.

My invention further seeks to provide the insulator with hoods or disk-like members movable relatively thereto, whereby the arcing distance may be varied and the hoods or disk-like members disposed to best advantage for the purposes above mentioned.

A further object of my invention is to produce an insulator provided with walls constructed of different materials, my primary object being to use in some instances for certain of the walls a non-fireproof material, thereby obtaining the highest possible insulating qualities combined with great strength and at the same time making the insulator practically fireproof, either on the inside or outside.

I do not limit myself in every instance to make the tube or wall 13 separable from the barrel 6 nor do I limit myself to having in every instance the bottom of the barrel integral with the main body portion, as various changes in construction may be made by those skilled in the art without departing from the scope or spirit of my invention.

Reference is to be had to the accompanying drawings, forming a part of this specification, in which similar characters of reference indicate corresponding parts in all the figures.

Figure 1 is a horizontal section through a partition provided with one of my improved insulators. Fig. 2 is a vertical section through the same, taken upon the line 2-2 of Fig. 1 looking in the direction of the arrow; and Fig. 3 is a view somewhat similar to Fig. 1 and showing the insulator with the hoods

and one of the insulating tubes removed therefrom.

A wall or partition is shown at 4 and is provided with a threaded aperture 5, into which is screwed a cylindrical barrel 6, of insulating material, preferably electrose, provided externally with a thread 7 extending throughout its entire length. This barrel 6 is provided, further, with a bottom 8 integral therewith. A pair of revoluble clamping-plates 9 are provided with annular projecting edges 10 and are threaded internally, so as to fit upon the thread 7 of the barrel 6. By turning these clamping-plates they may be screwed toward and from each other, and also toward and from the partition or wall 4. The annular washers 11 are of insulating material, preferably of soft rubber, and are clamped rigidly against the partition or wall 4 by pressure of the clamping-plates 9.

Disposed within the barrel 6 and concentric thereto is a tube 13, of insulating material, preferably glass, separated from the cylindrical barrel 6 by an air-gap 12, as indicated in Fig. 3. A closure-plug 14 fits the open end of the cylindrical barrel 6 and is threaded at 15 for such purpose, the interior of the barrel being similarly threaded. The plug 14 is provided with a centrally-disposed aperture 14^a, and the bottom of the barrel 6 is provided with a similar aperture 16. A sleeve 17, of insulating material, preferably porcelain, may be mounted intermediate of the tube 13 and the barrel 6 and concentric therewith, as indicated in Fig. 1. The tube 13 and the sleeve 17 are fitted against washers 18, 19, these washers being of soft rubber, as indicated in Fig. 1.

The only difference between the internal construction of the insulator as shown in Fig. 1 and as shown in Fig. 3 is that in Fig. 3 the sleeve 17 is omitted.

Apertures 20, 21 are provided for the purpose of allowing a circulation of air through the air-space 12 when said space is used. This maintains the interior of the cylindrical barrel 6 as dry as practicable. The hoods or disk-like members are shown at 22 and 24 and are threaded internally, so as to fit upon the exterior of the barrel 6. These hoods or disk-like members are provided with annular flanges 23 and 25, whereby they are virtually made larger, and thus serve to increase the arcing distance. The barrel 6, being removed from the wall 4 may be employed for any purpose for which an article of its char-

acter is needed. The washers 18 19, having more or less resiliency, as above described, serve to distribute the pressure against the tube 13 and the sleeve 17, so as to avoid danger of breakage of these members. The arrangement of the parts is such that the tube 13 is sunken into the oppositely-disposed ends of the barrel 6.

In order for a current to break through the complete composite structure, (shown in Fig. 1,) it must pass through the insulating-barrel 6, the sleeve 17, and the tube 13, together with a body of air inside of the tube 13 and encircling the conductor. The apertures 14^a and 16 being smaller than the tube 13 necessarily creates an air-jacket surrounding the conductor, which passes through these apertures. By making the barrel 6, the sleeve 17, and the tube 13 of materials having different dielectric constants I find that the aggregate insulating effect is greatly increased. By using fireproofing materials for these parts I render the insulator fire-proof, either internally or externally, or both, as desired.

Having thus described my invention, I claim as new and desire to secure by Letters Patent—

1. The combination of a cylindrical barrel provided with a bottom, and a closure member for said cylindrical barrel, said bottom and said closure member being provided with means for supporting a conductor and also provided with apertures.

2. An insulator, comprising a cylindrical barrel provided with a bottom, means for mounting said cylindrical barrel upon a partition, a closure-plug mounted within said cylindrical barrel, said closure-plug and said bottom of said barrel being provided with an aperture through which a conductor may be threaded, and a hood mounted upon said barrel and adjustable in relation thereto.

3. In an insulator, the combination of a body portion of insulating material, a tube mounted within said body portion and concentric thereto, means for spacing said tube relatively to said body portion, and a hood mounted externally upon said body portion and adjustable in relation to the same.

4. The combination of a partition provided with an aperture, a body portion of insulating material extending through said aperture and adjustable relatively to said partition, and a hood mounted upon said body portion and adjustable relatively thereto.

5. The combination of a partition, a cylindrical barrel extending therethrough, means for securing said barrel relatively to said partition, and a hood mounted upon said barrel and adjustable relatively to said partition.

6. An insulator, comprising a cylindrical barrel threaded externally and provided at one end of its ends with a bottom, clamping-plates threaded internally and engaging said

cylindrical barrel, and a closure member engaging said cylindrical barrel.

7. The combination of a cylindrical barrel threaded externally throughout its entire length, a partition provided with an aperture threaded internally; said partition engaging said cylindrical barrel, means for securing said cylindrical barrel rigidly in position relatively to said partition, and a hood mounted upon said cylindrical barrel.

8. An insulator, comprising a barrel composed of insulating material and provided with a bottom having a groove, a washer disposed within said groove, a tubular member of insulating material engaging said bottom and extending into said groove so as to engage said washer, and a closure member engaging said tubular member and said barrel.

9. An insulator, comprising a barrel composed of insulating material and provided with a bottom integral therewith, means for extending said barrel to a greater or lesser extent through a partition, a tubular sleeve mounted within said barrel, a tube mounted within said tubular sleeve, said tubular sleeve and said tube being of insulating material, and a closure member engaging said cylindrical barrel and adapted to exert pressure upon said tube and said tubular sleeve.

10. An insulator, comprising a barrel composed of insulating material and threaded externally, said barrel being provided at one of its ends with a bottom, and being threaded internally at its other end, and a closure-plug of insulating material provided externally with a thread and fitted into said threaded end.

11. An insulator, comprising a cylindrical barrel composed of insulating material and provided at one of its ends with a bottom and threaded internally at the other of its ends, a closure-plug threaded externally and fitted into said threaded end, a tube of insulating material clamped intermediate of said closure-plug and said bottom, and means for adjusting the general position of said barrel relatively to a position supporting the same.

12. The combination of a cylindrical barrel, a partition through which said barrel extends, a plurality of hoods mounted upon said barrel, and disposed upon opposite sides of said partition.

13. The combination of a partition, a cylindrical barrel extending entirely through said partition and adjustable relatively thereto, and a hood mounted upon said cylindrical barrel.

14. The combination of a partition, a barrel composed of insulating material and extending entirely through said partition and adjustable relatively thereto, and a hood of insulating material encircling said cylindrical barrel and adjustable thereupon.

15. The combination of a cylindrical barrel provided externally with a continuous

- thread extending from one end of said barrel to the other, a partition provided with a thread mating said thread of said cylindrical barrel, said partition being of such thickness that said barrel extends entirely through it, a clamping-plate mounted upon said tubular body portion and adapted to exert pressure against said partition, and a hood mounted upon said cylindrical body.
16. The combination of an insulator comprising a tubular body portion provided externally with a thread, a partition through which said tubular body portion extends, and a clamping-plate engaging said tubular body portion, and adapted to exert pressure upon said partition.
17. The combination of a partition provided with an aperture, a barrel composed of insulating material and extending entirely through said partition, said barrel being threaded externally, and revoluble clamping-plates mounted upon opposite sides of said partition and threaded so as to fit upon said body portion.
18. An insulator, comprising a casing made of insulating material and provided with a bottom, a resilient member of insulating material disposed within said casing, a tubular member of insulating material engaging said resilient member, and a closure member engaging said casing.
19. An insulator, comprising a casing made of insulating material provided with end portions, and a plurality of tubular members of insulating material disposed within said casing and intermediate of said end portions.
20. An insulator, comprising a casing made of insulating material and provided with end portions, and a plurality of tubular members of insulating material removably mounted within said casing and intermediate of said end portions.
21. An insulator, comprising a casing made of insulating material and provided with a lining, of a fireproof material.
22. An insulator, comprising a casing made of insulating material, said casing being provided with a plurality of linings, the said linings consisting of fireproof insulating materials.
23. An insulator, comprising a casing made of insulating material, said insulating material having a low softening-point, the said casing being provided with a lining of insulating material, said lining consisting of a material having a high softening-point.
24. An insulator, comprising a casing made of insulating material, said material having a low softening-point, the said casing being provided with a lining of fireproof insulating material.
25. An insulator, comprising a cylindrical tubing of insulating material threaded externally, and a plurality of clamping members threaded internally, engaging said casing.
- In testimony whereof I have signed my name to this specification in the presence of two subscribing witnesses.
